PLATING FIXTURE

James T. Saas, Rocky River, Ohio

Original application November 8, 1943, Serial No. 509,360. Divided and this application February 7, 1944, Serial No. 521,301

4 Claims. (Cl. 204—297)

This invention relates to electroplating apparatus, and more particularly to fixtures for supporting the articles to be plated in electrolytes.

The general purpose and object of the invention is to provide, for fixtures of the above nature, novel, simple and effective means for supporting cylindrical cathode elements in an electrolyte.

I accomplish the foregoing object in and through the construction and arrangement of parts shown in the drawing, wherein Fig. 1 represents a sectional view taken through an electroplating tank wherein my supporting means is shown and Fig. 2 a detail in section corresponding substantially to the line 2—2 of Fig. 1 and looking in the direction of the arrows.

Describing the various parts by reference characters, 1 denotes a positive bus bar and 2 a negative bus bar which are shown as extending above and spaced from the tank 3 containing the electrolyte, the level of which is indicated at 4. 5 denotes one of the opposite side members of a frame, each of the said side members being extended beyond the ends of the frame proper and each having its end bent upwardly and provided with a hook 6 for engagement with the bus bar 1. These sides members are connected by an end cross member 7 having at each end thereof a flange 7^a secured to a side member by a bolt 8. The opposite ends of the side members are connected to an end cross member 9 made of insulating material. 11 denotes a cathode hanger which is secured to the cross member 9, as by means of bolts 12, the said cathode hanger being provided with an upwardly extending hooked end 13 adapted to engage the negative bus bar 2. 14 denotes a cathode hanger which is secured to a plate 15 of insulating material as by means of bolts 16, the said plate being connected to and suspended from the central portion of the end cross member 7 as by means of bolts 17.

Each of the side members 5 is shown as provided with a plurality of holes 18 for the reception of the threaded ends of screw bolts 19 by means of which and a clamping plate (not shown) a suitable number of anodes 21 may be secured to each of the said side members, the anodes projecting downwardly into the electrolyte, preferably as far as the bottoms of the cathode hangers 11 and 14. Two such anodes are shown, for purposes of illustration.

25 is a supporting base in the form of a bar having its opposite ends secured to the cathode hangers 11 and 14 by means of bolts 23. Rigidly secured to said base, as by welding material 27,

is a semi-cylindrical clamping member 26. Adjustably secured to the base is the opposed semi-cylindrical clamping member 28, the adjustment of the same being obtained by providing the base of the said member with a flanged foot 29, preferably formed with the bottom or base of said member and resting upon the bar 25 and projecting toward and preferably having its outer end located within the confines of the member 26. This foot is provided with an opening 30 for the reception of a bolt 31, the opening being somewhat larger than the diameter of the bolt and the head 31^a of the bolt engaging the surface of the foot which is remote from the supporting base 25. The stem of the bolt extends through the said base 25 and is provided on the end thereof with a nut 32. Each of the clamping members 26 and 28 is provided with a plate or wall 33, 34 secured to the inner wall thereof, as by welding. These plates or walls extend substantially parallel with the edges of their respective members, and the plate or wall 33 is provided with a threaded opening 35 for engagement by the thread of a thrust bolt 36, which extends through the outer wall of the member 26 and is adapted to engage the plate or wall 34 with its inner end.

In practice, the external diameter of the tube-engaging cylinder which is formed when the edges of the members 26 and 28 are in contact will be only sufficiently less than the internal diameter of the tubular member within which the said members are to be inserted as to provide a good working clearance so that, when the members are separated or expanded, as indicated in the drawing, there will be a substantially unbroken contact between the exterior surfaces of the said members and the inner surface of the tubular or cylindrical member 37 (indicated in dot-and-dash lines) which is supported thereby. The external portions of the members 26 and 28 which are adapted to engage the inner surface of the tubular article 37 are shown as of less diameter than the remaining portions of the said members whereby shoulders 26^a and 28^a will be provided between the external surfaces of each of said members, which shoulders serve to assist in positioning the tubular object upon the clamping members.

From the foregoing, it will be evident that I have produced a simple and most efficient expandible clamp for tubular cathode members; also that various changes may be made in details of construction and design of the particular embodiments of my invention shown and described

herein but without departing from the spirit of my invention.

This application is a division of my application Serial No. 509,360, filed November 8, 1943.

Having thus described my invention, what I claim is:

1. In an electroplating apparatus, means for supporting a hollow object within the electrolyte of said apparatus, said means comprising a base bar adapted to form part of a cathode support, a hollow supporting member rigidly secured to said base bar, and a complementary hollow supporting member having a foot therewithin adapted to rest upon the base bar and projecting toward the interior of the other supporting member, the said supporting members having each an outer wall provided with an external surface shaped to conform to the inner surface of a hollow object to be supported thereby, a bolt extending through the base bar and through an opening in the said foot, a nut on said bolt for clamping the second supporting member to the base bar, and a bolt extending through the external wall of the first mentioned supporting member and adapted to engage an internal portion of the second supporting member thereby to separate the said members and to enable the external surfaces thereof to engage the inner surface of a hollow object to be supported thereby.

2. In an electroplating apparatus, means for supporting a hollow object within the electrolyte of said apparatus, said means comprising a base bar adapted to form part of a cathode support, a hollow supporting member rigidly secured to said base bar, and a complementary hollow supporting member having a foot therewithin adapted to rest upon the base bar and projecting toward the interior of the other member, the said supporting members having each an outer wall provided with an external surface shaped to conform to the inner surface of a hollow object to be supported thereby, means for adjustably clamping the foot of the second supporting member upon the base bar, and a bolt extending through the external wall of the first mentioned supporting member and adapted to engage an internal portion of the second supporting member thereby to adjust the relative positions of said members and enable the external surfaces thereof to engage the inner surface of a hollow object to be supported thereby.

3. In an electroplating apparatus, means for supporting a hollow object within the electrolyte of said apparatus, said means comprising a base bar adapted to form part of a cathode support, a hollow supporting member rigidly secured to

said base bar, and a complementary hollow supporting member having a foot therewithin projecting toward the interior of the other member and resting upon the base bar, the said supporting members having each an outer wall provided with an external surface shaped to conform to the inner surface of a hollow object to be supported thereby, a bolt extending through the base bar and through an opening in the said foot for clamping the second member adjustably upon the base bar, a wall extending across the interior of the first mentioned supporting member, a wall extending across the interior of the second supporting member and opposed to the wall within the first supporting member, and a bolt extending through openings in the walls of the first supporting member and having a threaded engagement with one of said walls and engaging the wall within the second supporting member whereby, by adjustment of said bolt, the ends of the supporting members which are remote from the base bar may be separated thereby to insure a substantially continuous clamping engagement of the outer surfaces of the same with the interior surface of a hollow article within which such ends are inserted.

4. In an electroplating apparatus, means for supporting a hollow object within the electrolyte of said apparatus, said means comprising a base bar adapted to form part of a cathode support, a hollow supporting member secured to said base bar, and a complementary hollow supporting member slidably mounted upon said base bar, means for clamping the second supporting member to said base bar, the said supporting members having each an outer wall provided with an external surface shaped to conform to the inner surface of a hollow object to be supported thereby, a wall secured to the interior of the first mentioned supporting member, a thrust wall secured to and within the second supporting member and opposed to the wall within the first supporting member, and a bolt extending through an opening in the outer wall of the first supporting member and through and having threaded engagement with an opening in the wall within the said member whereby, by adjustment of said bolt, the inner end thereof may engage the thrust wall within the second supporting member, whereby the ends of the supporting members which are remote from the base bar may be separated thereby to insure a substantially continuous engagement of the outer surfaces of the same with the interior surface of a hollow article within which the remote ends of the supporting members are inserted.

JAMES T. SAAS.
